(57) **CLAIM**

The ornamental design for a recurve riser as shown and described.

DESCRIPTION

FIG. 1 is an elevated perspective view of an archery bow riser showing my new design;

FIG. 2 is an elevated reverse perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top view thereof; and,

FIG. 8 is a bottom view thereof.

The broken lines showing of mechanical elements are included for environmental purposes only and form no part of the claimed design.
